THREADING TOOL HOLDER WITH SLIDABLE COVER ON HOLLOW HANDLE

William E. Cowley, Louisville, Ky., assignor to American Saw and Tool Company, Louisville, Ky., a corporation of Kentucky

Filed Dec. 8, 1958, Ser. No. 778,911

2 Claims. (Cl. 10—148)

The present invention relates to improvements in hand tools, and particularly, to a combination carrier and wrench for thread forming and like instrumentalities.

The object of the invention, in general, is to provide an improved wrench and carrier of economical manufacture and simple construction that facilitates storage and use of a plurality of thread forming instrumentalities, that is exceptionally compact, and that despite its compactness provides a wrench having a long effective lever arm.

In particular, it is an object of the invention to provide, in a wrench and carrier having an instrument holding jaw assembly and a wrench arm or handle, the improvement comprising the provision of a comfortably grasped handle that is relatively short and wide, hollow and open to one side or face thereof to define a laterally open recess or well adapted for reception of a plurality of thread forming instruments or members, and a cover for said recess mounted for movement relative to said handle to open said recess and expose to view the entire contents thereof for convenient selection of an appropriate instrument.

Another object of the invention is to provide, in a wrench and carrier embodying the improvement above defined, the further improvement that the cover for the laterally open storage well comprises a comfortably grasped hand grip that is slidably mounted on the handle for movement longitudinally outward to constitute an extension of the handle, whereby the cover together with the handle defines an elongate wrench arm for use in threading the associated instrument or thread forming member onto or into a work piece with minimum effort.

By virtue of the above defined improvements, the invention affords a tool having the advantages that the same constitutes an exceptionally compact storage vessel for a number of thread forming members, reveals all of the members without removal of the same from their storage well, facilitates convenient selection of a thread forming member, permits removal and insertion of the members without danger of damage thereto, and affords, despite its compactness as a storage vessel, a long effective lever arm when in use as a wrench.

A further and more specific object of the invention is to provide an improved wrench and carrier embodying the defined improvements and comprising an elongate unitary body member having a jaw receiving aperture centrally between the ends thereof and a pair of handles extending outwardly in opposite directions from said aperture, each handle having a laterally open recess therein occupying the major area thereof, each said recess being wider and deeper than the largest thread forming member to be stored and of a relatively short length, each recess being adapted to contain a plurality of thread forming members, and a unitary cover for each of said recesses slidably mounted on the respective handle for longitudinal sliding movement outwardly from a position covering the recess to a position wherein it constitutes an extension of the respective handle, said recesses opening at the face of said handles that is uppermost when the

2

tool is in use whereby said covers may be used as extensions of said handles without displacing the thread forming members stored in said recesses.

A still further object of the invention is the provision of an improved wrench and carrier as above defined wherein the covers are comprised simply of sheet metal parts retained on the body solely by frictional engagement therewith.

Other objects and advantages of the invention will become apparent in the following detailed description.

Now, in order to acquaint those skilled in the art with the manner of making and using my improved tool, I shall describe, in connection with the accompanying drawings, a preferred embodiment of the tool and preferred manners of making and using the same.

In the drawings:

Figure 1 is a perspective view of a preferred embodiment of a tap wrench and carrier formed according to my invention, the view being taken from the top and illustrating the condition of the same when simply storing taps;

Figure 2 is a perspective view of the tap wrench and carrier taken from the bottom;

Figure 3 is a perspective view taken from the same angle as Figure 1 and illustrating the condition of the tap wrench and carrier when in use;

Figure 4 is a perspective view of the tool with the recess covers and taps removed;

Figure 5 is a vertical longitudinal section of the tool;

Figure 6 is a cross-section of the tool taken substantially centrally thereof; and

Figure 7 is a cross-sectional view taken substantially on line 7—7 of Figure 5.

Referring now to the drawings, I have illustrated for purposes of disclosure a tap wrench and carrier embodying my present invention. As shown the preferred embodiment consists, simply, of an elongate unitary body 10, a tap holding jaw assembly 12 carried by the body centrally between the ends thereof, a plurality of taps 14 to be stored in the body to opposite sides of the assembly 12, and a pair of covers 16 carried by the body to opposite sides of the jaw assembly for retaining the taps in the body.

The body 10 preferably comprises a unitary casting, suitably zinc, having a centrally located rectangular frame portion 18 defining a transverse jaw receiving aperture 20. To opposite sides of the portion 18, the body includes a pair of outwardly extending handles or hand grip portions 22, which are preferably quite short and wide. The

faces of the handles 22, i.e., the surfaces perpendicular to the axis of the aperture 20, are preferably flat, and the sides of the handles are preferably convex. However, the exact configuration is not especially critical for purposes of the present invention. Within each of the

handles, I provide a laterally open recess 24 which preferably opens to one face of the respective handle and occupies the major part of the surface area thereof, whereby each recess is quite wide, but relatively shallow and short. The two recesses preferably open to the same

face of the tool and are preferably both of the same size. With regard to specific size, each recess is of a length and depth only slightly greater than the length and major diameter, respectively, of the largest one of the taps 14 to be stored, and of a width significantly greater than the

diameter of that tap, whereby each recess is adapted for reception therein of a plurality of taps in parallel substantially coextensive relation, and whereby the contents of each recess is readily ascertained by visual observation and without necessity for removing the taps from the recesses. The handles 22 of the body are dimensioned proportionally to the largest tap to be stored, whereby the handles are no longer, deeper, or wider than

required for compact storage of the desired number of taps.

The jaw assembly 12 is mounted within the aperture 20 of the body 10 and includes a stationary jaw 26, a movable jaw 28 and screw means 30 for effecting movement of the jaw 28. The frame portion 18 of the body is provided with flat interior surfaces, and the jaws 26 and 28 are similarly provided with flat sides and of a width to be conformably received between the opposite sides of the frame, whereby the jaws are retained against relative rotation within the frame. The movable jaw 28 is first installed in the aperture and includes a stem 32 adapted to extend through a hollow boss 34 provided at one side of the tool as part of the frame 18. Threaded into this boss, by means of a right-hand thread, is an externally projecting hollow adjusting stud 36, the interior of which has threaded connection, by means of a left-hand thread, with the stem 32 of the jaw 28, whereby the two threaded connections cooperate in advancing and retracting the jaw upon manual rotation of the outer end portion of the stud 36. After assembly of the jaw 28 and stud 36, the stationary jaw 26 is positioned in the end portion of the frame 18 opposite the boss 34, the jaw 26 being retained in the frame by means of a set screw 38 extending inwardly and downwardly through the frame 18 from one of the recesses 24, as shown in Figure 5. After assembly of the jaw 26, the jaw 28 is retained in the frame against disassociation from the tool by virtue of the threaded connections of the stem 32, the stud 36 and the boss 34, which are so assembled as to prevent disconnection of the threads except upon movement of the jaw 28 toward the position occupied by the jaw 26 after removal of the latter. The jaws 26 and 28 are provided centrally thereof with aligned V-shaped recesses defining a square socket for reception therebetween of the conventional square shanks of the taps 14, the jaws being adjustable to receive and clamp therebetween the shanks of a plurality of different sizes of taps.

The taps used in conjunction with the tool of the invention may be standard or conventional in all respects, and a selected number of taps of selected, commonly encountered sizes are preferably supplied with the tool.

The covers 16, since the handles 22 and recesses 24 are identical, are also preferably identical. Each cover, in the preferred embodiment of the tool, comprises a unitary sheet metal stamping of a length slightly greater than the length of one recess 24 but slightly less than the length of one handle 22. The cross-sectional configuration of each cover is of generally U-shape and complementary to the cross-sectional configuration of the handles 22. In particular, each cover preferably includes a flat, wide bight portion and a pair of outwardly convex-inwardly concave leg portions which are adapted to mate with and frictionally and slidably engage the sides of the handle on which mounted. The degree of curvature of the sides of the handles and the legs of the covers is preferably such that the covers can be snapped onto and off of the handles by movement transversely thereof. Generally, however, the predominant direction of movement of the covers is longitudinally of the handles, so that the covers may be slid, respectively, onto the handles from the outer ends thereof with the legs of the covers frictionally engaging the sides of the handles and the bight portions of the covers overlying the open sides of the respective recesses 24.

As thus mounted, the covers 16 normally close the recesses 24 and retain the taps 14 therein in compactly stored condition. When it is desired to use a tap, each cover may readily be slid independently of the other outwardly on the respective handle to open the respective recess and expose to view the entire contents thereof. Thus, selection of the appropriate tap is greatly facilitated, and there is no need to remove from the recesses any of the taps other than the selected one. The selected tap is then mounted between the jaws 26 and 28 of the

assembly 12, and the jaw 28 is clamped thereon by appropriate manipulation of the stud 36 to permit use of the body 10 as a wrench in threading the tap into a work piece. The tap is preferably mounted in the jaw assembly so as to extend from the face of the tool opposite the face to which the recesses open, so that the covers 16 may be extended and the recesses left open without resulting in displacement of the stored taps, at least when tapping downwardly into the wall of a generally upright bore. The body 10 is employed as a hand grip in a conventional manner in initially starting the tap in the bore. As resistance to threading increases, the operator may shift his hands to the handles 22 in order to apply greater force to the tap. As threading resistance increases still further, the operator may slide the covers 16 outwardly toward the outer ends of the handles to a position wherein the covers constitute longitudinal extensions of the handles, whereupon the operator may utilize these extensions, with the attendant advantage of longer lever arms, in applying maximum force to the tap. As extended, the covers have substantially rigid engagement with the handles, due to the mating engagement of the two, whereby use of the covers as extensions of the effective wrench arm is facilitated. Due to the configuration thereof, both the handles and the covers afford convenient hand grips for the operator. After threading is completed, the tap employed is conveniently returned to one of the recesses 24, the covers 16 are slid closed, and the tool is returned to its original or normal condition.

Thus, the present invention provides a short, compact tool that is but slightly longer than would be necessary simply for storage in each handle thereof of a single tap, that stores a large number of taps in this short length and in a conveniently and readily accessible manner wherein the taps are protected from abuse and are not required to be inserted or removed in such manner as would damage their threads, that exposes all of the taps to direct view while in their storage wells and facilitates removal of a selected tap without necessity for removal of the remainder of the taps, and that, despite its compactness, affords exceptionally long lever arms for use in applying a selected tap to a work piece. As is obvious, all of these advantages would likewise be attained by application of the described improvements to a single arm tap storing and manipulating tool, and to the functions of storing and manipulating thread forming dies. Moreover, the tool of the invention consists of a minimum number of parts, each manufactured and assembled in a most simple manner. Accordingly, it has been shown herein that the objects and advantages of the invention are obtained in a convenient, economical and practical manner.

While I have shown and described what I regard to be the preferred embodiment of my invention, it is apparent that various changes, rearrangements and modifications may be made therein without departing from the scope of the invention, as defined by the appended claims.

I claim:

1. A tool for storing and manipulating thread forming members and the like comprising an elongate unitary body member having a jaw-receiving transversely-apertured frame centrally between the ends thereof and a pair of handles extending outwardly in opposite directions from said apertured frame, said handles each being relatively short, having two oppositely disposed convex sides and having a laterally open storage recess therein occupying substantially the full area thereof, each recess opening solely to one face of the respective handle between said convex sides and both recesses opening to one face of said body to which said apertured frame opens, each of said recesses being relatively wide and deep and adapted for reception therein of a plurality of thread forming members, and a cover for each of said recesses comprising a member having a generally U-shaped cross

sectional configuration including a flat wide bight portion to overlie the recess opening and a pair of outwardly convex-inwardly concave leg portions adapted to mate with and frictionally engage the convexed sides of the respective handles, said covers having a length greater than the length of the recess in the respective handle and normally closing the recess, said cover being slidable outwardly on the respective handle to open the recess and expose the contents thereof to view, each cover when slid outwardly on the respective handle constituting a 10 longitudinal extension thereof and together with the handle providing a long wrench arm for the tool.

2. A tool as set forth in claim 1 for storing and manipu-

lating taps, wherein each of said recesses is wider and deeper and only slightly longer than the longest tap to be stored and is adapted for reception therein of a plurality of taps in parallel side by side substantially co-extensive relation.
